UNITED STATES PATENT OFFICE.

JOB C. BARTLETT, OF PITTSBURG, PENNSYLVANIA, ASSIGNOR TO THE J. C. BARTLETT COMPANY, OF SAME PLACE.

DESIGN FOR A LID FOR STOVES OR RANGES.

SPECIFICATION forming part of Design No. 34,148, dated February 26, 1901.

Application filed November 12, 1900. Serial No. 36,298. Term of patent 14 years.

To all whom it may concern:

Be it known that I, JOB C. BARTLETT, a resident of Pittsburg, in the county of Allegheny, State of Pennsylvania, have invented and produced a new and original Design for Lids for Stoves or Ranges; and I do hereby declare the following to be a full, clear, and exact description thereof, reference being had to the accompanying drawings, in which—

10 Figure 1 is a top view of a lid for stoves and ranges embodying my design. Fig. 2 is a cross-section thereof on the line 2 2, Fig. 1, and Fig. 3 is a bottom view of the same.

15 The leading feature of my design consists in a lid for stoves and ranges having the shape and form substantially as herein shown and described.

20 As illustrated in the drawings, 1 represents the lid for stoves and ranges, which is provided with the recess 2, formed in the edge 3 thereof and extending from the face 4 of said lid entirely through the same, said recess

being formed with angular ends 5. An annular flange 6 and annular recess 6' are formed on the bottom 7 of said lid 1, and a circular 25 rim 8 is formed on said bottom 7 adjacent to the edge 3 of said lid 1. A lifter-opening 9 is formed in the center of the face 4 of said lid 1.

Having described my invention, what I 30 claim as new, and desire to secure by Letters Patent, is—

The design for a lid for stoves and ranges, substantially as herein shown and described.

In testimony whereof I have hereunto 35 signed my name to this specification, in the presence of two subscribing witnesses, at Pittsburg, in the county of Allegheny and State of Pennsylvania, this 8th day of November, 1900.

JOB C. BARTLETT.
